*By
S. Linger, Atty.*

UNITED STATES PATENT OFFICE.

ALEXANDER BURNET, OF LONDON, ENGLAND.

HAIR NET OR CAP.

Application filed May 25, 1923. Serial No. 641,417.

To all whom it may concern:

Be it known that I, ALEXANDER BURNET, a subject of the King of Great Britain, of 18 Golden Lane, London, E. C. 1., England, have invented new and useful Improvements in or Relating to Hair Nets or Caps, of which the following is a specification.

This invention relates to hair nets and has for its object to provide a combined hair net and cap for outdoor wear adapted in use to present the appearance of an ornamental head band and enabling a great variety of fabrics to be employed in its construction.

According to the invention a cap is provided, the crown of which is constituted by a hair net formed in any usual manner whilst the lower edge comprises a band of netted, crocheted, woven, knitted or other like material arranged so as to adapt itself to fit closely around the head.

Reference will now be made to the accompanying drawing which illustrates by way of example a cap constructed according to the invention.

In the example illustrated, the crown of the cap or hair net proper *a* may be formed with real hair, silk or other convenient material, and may be of varying or uniform mesh and of single or multiple strand. To the outer meshes of this net *a* is attached an ornamental band *b* which may be of woven, knitted, crocheted, netted or any like fabrics

to these provided that the texture is sufficiently loose to allow the band to stretch and contract readily in fitting it in position. The outer edge of this band is provided with a continuous elastic thread enclosed within the seam *c* so that the elastic material itself is hidden.

In use the device has the appearance simply of an ornamental band, the hair net portion serving the dual purpose of maintaining the hair in place over the crown of the head and of supporting the ornamental band against displacement and is itself practically invisible. In this manner the ornamental band is retained closely around the head without any unnecessary tightness such as is ordinarily produced by pinning or tying. Furthermore, the invention enables the ornamental band to be made in a variety of wide meshed designs as the elastic edging and hair net support always tend in use to maintain the band in fully distended condition.

I claim:

A cap for personal wear comprising a crown portion of hair net material, an ornamental bandeau attached to the edges of said crown portion and an elastic edging to said bandeau.

In witness whereof I affix my signature.

ALEXANDER BURNET.
